FOREIGN PATENT DOCUMENTS

DE 1085810 7/1960

1 Claim, 3 Drawing Sheets

(57) **CLAIM**

The ornamental design for the tool container, as shown and described.

DESCRIPTION

FIG. 1 is a perspective view illustrating a tool container in accordance with the present invention;

FIG. 2 is a front view illustrating the tool container of FIG. 1;

FIG. 3 is a back view illustrating the tool container of FIG. 1;

FIG. 4 is a top view illustrating the tool container of FIG. 1;

FIG. 5 is a bottom view illustrating the tool container of FIG. 1;

FIG. 6 is a left side view illustrating the tool container of FIG. 1; and,

FIG. 7 is a right side view illustrating the tool container of FIG. 1.

The broken lines showing various portions such as the sliding locking mechanism are for illustrative purposes only and form no part of the claimed design.
